UNITED STATES PATENT OFFICE.

HUGH R. BAILEY, OF CARVER, MASSACHUSETTS.

CRANBERRY SEPARATOR.

Application filed August 8, 1922. Serial No. 580,399.

To all whom it may concern:

Be it known that I, HUGH R. BAILEY, a citizen of the United States, residing at Carver, in the county of Plymouth and 5 State of Massachusetts, have invented new and useful Improvements in Cranberry Separators, of which the following is a specification.

The chief object of this invention is to 10 provide an improved machine for separating cranberries into firsts and seconds, and separately delivering these grades.

Another object is to separate from the firsts the smaller berries, known as pie 15 berries, and to deliver these separately.

The invention is embodied in the improvements hereinafter described and claimed.

Of the accompanying drawings forming 20 a part of this specification,—

Figure 1 is a side elevation of a separating machine embodying the invention.

Figure 2 is a fragmentary elevation, looking from the opposite side.

25 Figure 3 is a fragmentary vertical section, showing the upper portion of the machine.

Figure 4 is a side view, showing one of the wipers hereinafter described, and the 30 mechanism for adjusting the same.

Figure 5 is an enlargement of a portion of Figure 3.

The same reference characters indicate the same parts in all of the figures.

35 The machine includes a vertically elongated frame, including uprights 12, and cross-bars 13. Fixed to the frame is a vertically elongated casing, including spaced apart upright side portions 14, between 40 which the separator units hereinafter described, are located. The rear side of the casing, at which the bounding boards hereinafter described, are located, may be open, to permit inspection of the interior. Above 45 the casing is a hopper, which includes oppositely inclined members 15 and 16, the lower ends of which are spaced apart to form a contracted outlet 17, extending across the hopper. The delivery of cran-

50 berries through the outlet is controlled by a horizontal fluted feed roll 18, obstructing a part of the outlet, and in close proximity to the lower end of the member 15, and spaced from the lower end of the member 55 16. A yielding inclined wiper is tangen-

tially arranged relative to the roll, as shown by Figure 3, and is preferably composed of a resilient sheet metal strip 19, the resilience of which is increased by slots 20 (Figure 4), and a flexible rubber strip 21, resting loosely on the upper surface of the strip 19. Said strips are attached to a slide 22, which is movable on the under side of the member 16, to vary the position of the wiper relative to the roll.

I employ parallel motion mechanism to 60 adjust and move the slide, and confine it at different adjustments, said mechanism including levers 23, pivoted at 24 to the hopper, and at 25 to ears on the slide, and a hand lever 26, connected by a link 27 with the outer end of one of the levers 23, and by links 28, with the inner ends of the levers, the arrangement being such that 65 when the lever 26 is moved by the operator in the direction indicated by the arrow in Figure 4, or in the opposite direction, a corresponding movement is imparted to the slide 22, so that the wiper is moved edge-wise toward or from the perimeter of the roll 18, and is frictionally retained at any 70 position in which it is left, the edge of the wiper being maintained parallel with the axis of the roll.

75 Cranberries contained in the hopper enter the throat 17, and bear on the roll 18, and on the wiper. The roll is rotated in the direction of the arrow marked thereon, and cooperates with the wiper in feeding the berries, so that they drop separately.

80 The machine is provided, as usual, with a vertical series of bounding-boards 30, on to which the berries fall, and with means cooperating with these boards for guiding the berries, which rebound from the boards to 85 an outlet where they are collected, the berries being automatically assorted or graded by the height to which they rebound. The berries rebound from each board sufficiently to pass over a baffle-board 31, associated with a deflector 36, the baffle-board and deflector being separated from the lower edge of the bounding-board by a throat 32. The berries crossing the baffle-board 31 are guided by a series of inclines 34, and a stepped conduit, composed of sections 33, to a suitable point of delivery, as usual. Guiding means including the inclines and conduits being well known in this art, the same need not be 90 particularly described. The conduit sec- 100 105 110

tions 33 form the front side of the casing, and the berries delivered by the lower conduit section pass to an outlet at 35 (Figure 1), these including the firsts or larger berries.

Vertical guiding slots 39, are provided in the sides 14 of the casing, and the ends of the baffle-boards 31 are extended through the slots, the length of the slots being such that 10 the baffle-boards may be adjusted therein to a considerable extent, so that the upper edges of the baffle-boards may be either flush with the upper edges of the deflectors 36, as shown by Figure 3, or raised more or less 15 above the deflectors. With the ends of the baffle-boards are rigidly connected vertical bars or slides 40, provided with offset threaded bolts 41. Said bolts pass loosely through orifices in fixed brackets 42, on the 20 casing, and are provided with nuts 43, bearing loosely on the brackets, so that the slides 40 are supported by the brackets, and may be vertically adjusted by turning the nuts.

Each bounding-board 30 and the deflector 25 36, and baffle-board 31, associated therewith, constitute elements of a separator unit which, as thus far described, is not new with me. Heretofore the berries which do not rebound over the baffle-board of any unit, 30 have dropped loosely through the throat 32, and may or may not fall properly on the bounding-board of the next lower unit.

I have added to each unit means for controlling the delivery of berries from unit 35 to unit, said means preferably including a fluted horizontal feed roll 44, similar to the roll 18, and located at the lower edge of the deflector 36, and a longitudinally arranged yielding wiper, cooperating with the roll 44. 40 I prefer to make the wiper in the form of a brush, composed of a head 45, and bristles 47 (Figure 5.) The head is pivoted at 48 to the sides of the casing below the bounding-board, and the wiper is pressed yielding 45 ingly against the roll 44 by a spring 49. The berries that roll from the bounding-board without passing over the baffle-board, and those which roll down the deflector 36, are caused by the cooperation of the roll 44 and its wiper to drop vertically on to the 50 bounding-board of the next lower unit, the wiper brush yielding to permit a regulated delivery of the berries.

It will be seen that the wiper accompanying 55 the hopper feed roll 18 has to support a part of the weight of the mass of berries in the hopper. For this reason the wiper is of the reinforced construction shown and described, the portion of the wiper contacting 60 with the berries being the free edge of the rubber strip 21. This strip is reinforced and backed by the slotted resilient metal strip 19, which is sufficiently stiff to support the pressure of the mass of berries. The 65 wiper accompanying the roll 44 of a sepa-

rator unit is not required to support a mass of berries, so that its pressure is relatively light.

The several feed rolls, including the roll 18, are rotated in unison. The shaft 18^a of 70 the upper feed roll 18 has a pulley 50 (Figure 2), driven by a belt 51, from a pulley 52, on a driven shaft 53. The shaft of each feed roll has a sprocket wheel 54, engaged by an elongated sprocket chain 55, driven 75 by the shaft 18^a of the upper feed roll. One of the stretches of the chain 55 is pressed inward by rolls 56, on the free ends of spring-pressed swinging arms 57, to keep the chain suitably engaged with the sprocket 80 wheels.

The machine may include any desired number of separator units, five being shown by Figure 1. The three units at the upper end of the series, and the conduit composed 85 of the stepped sections 33, care for the firsts, which are delivered by the lowest conduit section, and pass across an inclined screen 58, on their way to the outlet 35. Said screen, which is preferably composed 90 of parallel wires, is formed to permit smaller or pie berries mingled with the firsts, to pass through it, and drop through an outlet 59, under the screen. Berries fall from the lowest conduit section 33 upon an inclined 95 guide 60, extending from under said section to the higher edge of the screen 58, and preferably composed of enameled cotton cloth, the berries rolling down said guide onto the screen, and rolling from thence over a similar inclined guide 61 to the outlet 35.

To prevent the pie berries from sticking in the openings of the screen, I provide a rotary brush, composed of bars 62, fixed to arms 63, radiating from a shaft 64, and 105 bristles 65, fixed to said bars, and adapted to sweep across the screen. I prefer to press the screen yielding upward to a limited extent, to enable the bristles 65 to more effectively dislodge pie berries sticking in the 110 screen. To this end, the screen is attached to the free end portions of arms 66, which are pivoted at 67 to fixed supports in the casing, and are pressed upward by springs 115 68 against a fixed stop 69. The arms 66 have curved portions 70, bridging the under side of the screen, and spaced therefrom.

The two separator units at the lower end 120 of the series care for the seconds, and the smallest or refuse berries. Nearly all of the seconds rebound from the bounding-board of the next to the lowest unit on to an incline 71, and pass from thence through a conduit 72, to the seconds outlet 59^a. The low grade berries, including decayed berries which do 125 not rebound, passing from the last-mentioned unit, and any seconds which have not been previously collected, are disposed of by the lowest unit, the seconds rebounding from the bounding-board of this unit, and falling 130

on to an inclined guide 73, whereby they are conducted to the seconds outlet 59^a. The lowest unit does not include the feed roll and the wiper elements of the other units, and the 5 berries falling from the bounding board of this unit, drop on to an inclined guide 74, and are conducted thereby to an outlet at 75. The baffle-boards of the lowest units may be independently adjusted by means including 10 slides 40^a, and connections between said slides and the casing, said slides and connections being similar to the slides 40, and the connections between the latter and the casing.

15 I find it desirable to provide means for varying the inclination of the bounding-boards 30, excepting the upper board, some lots of berries requiring a greater inclination of the bounding-boards than other lots. 20 I provide for this variation by pivoting the bounding-boards at 30^a to the casing, and at 30^b to vertical connecting bars 76, which are vertically movable on the casing, and are provided with hooks 77, adapted to engage 25 studs 78, such as ordinary wood screws or nails inserted in the sides of the casing, said studs being inserted after the proper inclination of the bounding-boards has been ascertained.

30 As heretofore, a fan blower is provided to force air through the berries between the hopper feed roll 18, and the bounding-board of the highest unit, to expel leaves, etc., from the falling berries, the blower including a 35 rotor 79, on a shaft 80, and a casing 81, having an outlet 82.

The main shaft 83 of the machine is driven by a belt 84, and drives the shaft 53, through a belt 85, and suitable pulleys. The shaft 40 53 is provided with a pulley 86, connected by a belt 87 with a pulley on the fan shaft 80, and with a pulley 88, connected by a belt 89 with a pulley on the brush shaft 64.

I regard as of the essence of the invention 45 the provision of means for causing berries falling from each separator unit to drop at a predetermined point on the bounding-board of the next lower unit, so that the berries rebound accurately in a predetermined path.

50 This is insured by the fluted feed rolls and the yielding wipers, constituting elements of the separator units. These fluted feed rolls and wipers are adapted to position elongated or elliptical berries, and cause them to fall sideways instead of endwise. Sidewise falling is 55 very desirable, because an elliptical cranberry striking a bounding-board on end, will not rebound as far as when it strikes the bounding-board sidewise.

60 I do not limit myself to a feed roll which is fluted. The yielding wiper may cooperate with a feed roll which is not fluted, although not so effectively. Any equivalent controlling means causing a similar regulated or 65 controlled delivery of the berries from each

unit, so that they will drop on the bounding-board of the next lower unit, at a predetermined point, may be employed.

It will be seen that the feed roll 44 and the yielding wiper constitute an embodiment 70 of a controlling means located below the throat 32, and adapted to first arrest the berries falling through the throat, then move the berries laterally to a point vertically above the bounding board 30 of the next 75 lower unit, and then release the berries and allow them to drop vertically upon the said lower board. I therefore provide for the uniform impingement of the dropped berries on each of the bounding boards of the series, and for a uniform distribution of said berries, so that they drop independently 80 without interference with each other.

It will also be seen that the said controlling means is adapted to deprive the falling 85 berries of momentum and then allow the berries to drop vertically, without previously acquired momentum, upon the bounding-board of the next lower unit, so that falling berries, having an appreciable degree of 90 resilience, are caused to rebound accurately from a bounding-board upon which they drop vertically from the controlling means of the next higher unit.

I claim:

1. A cranberry separator including a vertical series of separator units, each unit comprising, in combination, an inclined bounding board, a deflector spaced from the lower edge of the bounding board by a throat 100 through which fall the berries dropping directly from the bounding board, and those deflected by the deflector, and controlling means below the throat, adapted to first arrest the falling berries, then move the berries laterally to a point vertically above the bounding board of the next lower unit, and then release the berries and allow them to drop vertically upon said lower bounding board, the boards of the several units being 105 arranged with their lower edges in a common vertical plane.

2. A cranberry separator including a vertical series of separator units, each unit comprising, in combination, an inclined bounding board, a deflector spaced from the lower edge of the bounding board by a throat 110 through which fall the berries dropping directly from the bounding board, and those deflected by the deflector, a driven feed roll 115 below and obstructing the throat, and adapted to arrest the falling berries and laterally move the same to a point vertically above the bounding board of the next lower unit, and a yielding wiper bearing on one side of the roll, and co-operating with the latter to release the berries after their lateral movement, and allow them to drop vertically upon said lower bounding board, the boards 120 of the several units being arranged with 125 130

their lower edges in a common vertical plane.

3. A cranberry separator including a vertical series of separator units, each unit comprising, in combination, an inclined bounding board, a deflector spaced from the lower edge of the bounding board by a throat through which fall the berries dropping directly from the bounding board, and those deflected by the deflector, a driven feed roll below and obstructing the throat, and adapted to arrest the falling berries and laterally move the same to a point vertically above the bounding board of the next lower unit, and a yielding wiper bearing on one side of the roll, and cooperating with the latter to release the berries after their lateral movement, and allow them to drop vertically upon said lower bounding board, the boards of the several units being arranged with their lower edges in a common vertical plane, and means for simultaneously rotating the rolls of the several units.

4. A cranberry separator including a casing, a vertical series of separator units, each unit comprising, in combination, an inclined bounding board, a deflector spaced from the lower edge of the bounding board by a throat through which fall the berries dropping directly from the bounding board, and those deflected by the deflector, controlling means below the throat, adapted to first arrest the falling berries, then move the berries laterally to a point vertically above the bounding board of the next lower unit, and then release the berries and allow them to drop vertically upon said lower bounding board, the boards of the several units being arranged with their lower edges in a common vertical plane, and means on the casing for conducting berries rebounding from said boards, and delivering the same at one side of the series of units.

45. A cranberry separator, including a casing, a series of separator units arranged to permit berries to fall from unit to unit throughout the series, each unit comprising, in combination, an inclined bounding board from which some of the berries rebound, so that they pass away from the unit, a deflector spaced from the lower edge of the bounding board by a throat through which the remaining berries fall, and controlling means at the lower portion of each unit, adapted to arrest the falling berries, thereby depriving the same of momentum, and then allow the berries to drop vertically, without previously acquired momentum, upon the bounding board of the next lower unit.

6. A cranberry separator, including a casing, a series of separator units arranged to

permit berries to fall from unit to unit throughout the series, each unit comprising, in combination, an inclined bounding-board, from which some of the berries rebound, so that they pass away from the unit, a deflector spaced from the lower edge of the bounding-board by a throat through which the remaining berries fall, a driven feed roll below and obstructing said throat, to arrest the falling berries, and thereby deprive the same of momentum, and a yielding wiper bearing on one side of the roll, and cooperating with the latter to release the berries and allow them to drop vertically, without previously acquired momentum, upon the bounding-board of the next lower unit.

7. A cranberry separator, including a casing, a series of separator units arranged to permit berries to fall from unit to unit throughout the series, each unit comprising, in combination, an inclined bounding-board from which some of the berries rebound, so that they pass away from the unit, a deflector spaced from the lower edge of the bounding-board by a throat through which the remaining berries fall, a driven feed roll below and obstructing said throat, to arrest the falling berries, and thereby deprive the same of momentum, a yielding wiper bearing on one side of the roll, and cooperating with the latter to release the berries and allow them to drop vertically, without previously acquired momentum, upon the bounding-board of the next lower unit, and means for simultaneously rotating the rolls of the several units.

8. A cranberry separator, including a casing, a series of separator units arranged to permit berries to fall from unit to unit throughout the series, each unit comprising, in combination, an inclined bounding-board from which some of the berries rebound, so that they pass away from the unit, a deflector spaced from the lower edge of the bounding-board by a throat through which the remaining berries fall, a driven feed roll below and obstructing said throat, to arrest the falling berries, and thereby deprive the same of momentum, a yielding wiper bearing on one side of the roll, and cooperating with the latter to release the berries and allow them to drop vertically, without previously acquired momentum, upon the bounding-board of the next lower unit, means for simultaneously rotating the rolls of the several units, and means on the casing for conducting and delivering berries rebounding from said boards.

In testimony whereof I have affixed my signature.

HUGH R. BAILEY.
